FIG. 1.

FIG. 2.

Inventor,
Philip A. Geier,
d. A. Geier

Attorney

UNITED STATES PATENT OFFICE.

PHILIP A. GEIER, OF CLEVELAND, OHIO, ASSIGNOR TO THE P. A. GEIER COMPANY, OF CLEVELAND, OHIO, A CORPORATION OF OHIO.

PRESS-BODY.

1,350,649.

Specification of Letters Patent. Patented Aug. 24, 1920.

Application filed February 13, 1917. Serial No. 148,423.

To all whom it may concern:

Be it known that I, PHILIP A. GEIER, a citizen of the United States, residing at Cleveland, in the county of Cuyahoga and 5 State of Ohio, have invented certain new and useful Improvements in Press-Bodies, of which the following is a specification, reference being had to the accompanying drawings as well.

10 My invention relates to improvements in press bodies, and has for its object the construction of a cast body which is adapted to afford maximum movement for the thrust block, and one that is hollow interiorly, yet 15 suitably shaped to resist the strains and stresses of heavy service.

My improvement is herein explained and shown in connection with a straightening press; the body of which is formed of a 20 hollow casting reinforced in cross section at such points exteriorly and interiorly, as will best stiffen and strengthen the same against excessive strains, while avoiding any interference with the free operation of 25 the press upon all classes of work.

Specifically, my improvement is embodied in a press body wherein the base and upright are hollowed out in the portions of minimum stress while the front inner wall 30 of the upright is thickened above and below the jaws of the press body and the upper jaw, moreover, is provided with side fillets permitting the thrust block to be elevated to the maximum capacity of the press, while 35 affording extreme stiffness and strength at the upper angle of the jaw. My invention may be explained as thus embodied in connection with the accompanying drawings, wherein:—

40 Figure 1 is a view in front elevation, of a straightening press constructed in accordance with my invention.

Fig. 2 is a median cross sectional view thereof.

45 Throughout the drawings, I have employed the same character of reference to indicate similar parts.

The press body *a* is formed of an integral casting having an expanded base portion *b* extending laterally to form a bed, in which are recesses *b'* and *b''*. The upright portion contains thickened members *a'*, *a''* of relatively heavy cross section, protruding into the cavity *a'''*. These members, it will

be seen, are disposed at the upper and lower 55 angles of the press jaw, or in the zones thereof, in such relation thereto as experience has shown to be most efficient in resisting the excessive strains to which the press body is subjected. Preferably these members are convex; the lower one being of 60 heavier cross section for a reason that will later appear herein.

In order that the thrust block *c* carried at the extremity of the screw *d* and operated 65 by the hand wheel *d'* or bar *d''*, may have its maximum elevation and movement, within the limits of the press, lateral fillets *f* are integrally cast at the upper angle of 70 the jaw. These in coöperation with the interior reinforcing member *a'* sufficiently strengthen the press to resist strains equally at the upper and lower angles of the jaw, while interfering in no respect with the travel of the thrust block *c*, which may be 75 made of such size and shape, if desired, as will fit completely within the upper angle of the press jaw. The lower jaw is provided with a relatively larger reinforcing member *a''*, which with the widened or flaring 80 form of the lower portion of the upright, is substantially equal in resistance to the reinforcing members *a'*, *f*, *f*. Almost of necessity, the lower jaw or bed portion of the press must be substantially rectangular in 85 vertical section, to afford room at the rear of the bed, but the lower portion of the upright admits of ready extension laterally, so that the extra cross-section of metal may be provided if desired, without the reinforcing 90 member *a''*, but ordinarily I prefer the type shown.

From the foregoing it will be appreciated that the press body may be made much lighter and yet resist the strains necessarily 95 placed thereon. Moreover, the upper angle of the jaw is left of rectangular form interiorly, not only for the accommodation of the thrust block, but also affords a cylindrical and easily accessible socket for the 100 removable nut *e*, which is held in position within the upper jaw of the press by the set screw *e'*.

While I have explained the preferred disposition and relation of the reinforcing 105 members, I do not desire to be understood as necessarily restricting my invention thereto, inasmuch as one or more of said mem-

bers may be omitted and their relation may be altered, without departing from the spirit of my invention.

Having now described mechanism embodying my invention, I claim as new and desire to secure by Letters Patent, the following:—

1. A press body integrally formed of a casting hollow in its upright portion and 10 interiorly reinforced transversely approximately in the zones of the upper and lower angles of the press jaw, and exteriorly reinforced integrally at the sides only of the upper angle thereof, whereby adequate 15 working space is afforded therebetween, substantially as set forth.
2. A press body formed of a hollow casting having exterior lateral reinforcements cast at the angle of the upper jaw at a 20 distance from each other to afford adequate working space therebetween, and an interior reinforcement cast approximately in the zone of the bed or lower jaw of said press, substantially as set forth.
3. A press body comprising an integral hollow casting affording a bed and an overhanging upper jaw; the latter being strengthened by lateral fillets at its angle at a distance from each other to afford adequate 25 working space therebetween, and by an interior reinforcement positioned adjacent to the angle of said upper jaw, substantially as set forth.
4. A straightening press comprising a 30 hollow body cast with interior reinforce-

ments adjacent to the angles of the jaw and side fillets affording the maximum travel of the thrust block into engagement with the upper jaw, and a removable nut, a screw 40 therein, and a thrust block actuated by said screw between the jaws of the press, substantially as set forth.

5. A press body comprising a hollow casting having substantially rectangular upper and lower jaws with angular lateral fillets 45 reinforcing the angle of the upper jaw spaced apart from each other, and an interior reinforcing section cast in the zone of the lower jaw, in combination with a traveling member adapted to be elevated 50 substantially into engagement with the upper jaw between the lateral fillets.

6. In a press of the class described, the combination with a hollow upright body cast with substantially rectangular jaws, interior reinforcing members substantially at the angles of said jaws, and lateral fillets uniting the exteriors of the upper jaw with the body, of a member positioned between said fillets in its uppermost travel and 60 adapted to be actuated toward the lower jaw, a removable nut within the upper jaw, and a screw reacting therein against said member.

In testimony whereof I do now affix my 65 signature in the presence of two witnesses.

PHILIP A. GEIER. [L. S.]
